UNITED STATES PATENT OFFICE.

JOHN PRESTON FOSTER AND ALBERT F. MISENER, OF PAIA, TERRITORY OF HAWAII.

CONTINUOUS DISTILLING APPARATUS.

Application filed August 1, 1921. Serial No. 489,142.

To all whom it may concern:

Be it known that we, JOHN P. FOSTER and ALBERT F. MISENER, citizens of the United States, residing at Paia, Maui, Territory of Hawaii, have invented certain new and useful Improvements in Continuous Distilling Apparatus; and we do hereby declare the following to be a full, clear, and exact description of the invention, such as will 5 enable others skilled in the art to which it 10 appertains to make and use the same.

This invention relates to certain improvements in distilling apparatus, and particularly to a continuous still for the recovery 15 of crude alcohol for commercial purposes, such as motor alcohol, where it is necessary to produce the highest possible amount of combustible of the highest proof.

The principal object of the invention is 20 the provision of an apparatus of the character indicated which will be inexpensive to build and of such simple construction that the same may be readily assembled and set up without the assistance of experts, 25 which is an important factor where motor alcohol is produced in more or less isolated localities, a substantial portion of the apparatus being constructed of wood, as the quality, odor, flavor, etc., is of no importance 30 whatever, the quantity and proof only being desired, and consequently an expensive copper fractionating still is entirely out of place and unnecessary in this industry.

The still of the present invention is of that 35 type in which the distilling column comprises a series of chambers, through which the liquid and the vapor or gases flow in opposite directions for the separation of the two, said chambers being provided with 40 suitable openings and connections for the purpose. One of the essential features of such a still is the bubbling floor provided for each chamber. This floor has one or more capped openings, normally sealed by 45 a liquid-level maintained in the chamber, through which the vapor flows upwardly and is deflected below the liquid-level. The vapor bubbling through the fluid is freed from the fluid particles carried by it into the 50 liquid. The efficiency of the still depends to a considerable extent upon the area of this bubbling floor. When the liquid area is extensive, the vapor can spread out and take a longer course through the liquid with the

consequent greater elimination of the liquid 55 particles. Should the liquid area be circumscribed, the spreading of the vapor would be restricted and its travel through the liquid shortened, resulting in a lessened elimination of the liquid particles. 60

In stills of the type under consideration, in ordinary use the distilling column is mounted in a perpendicular position. In the present invention the distilling column is inclined at an angle between the perpendicular 65 and horizontal, preferably about 30° from the horizontal. With the column so inclined, the floors of the several chambers are horizontally positioned, thereby greatly increasing the area of the bubbling floors 70 over what it would be with the column perpendicular, and without increasing the axial cross-area or the volumetric capacity of the column. Also, by inclining the distilling column, particularly so when a plurality of them is used, space is economized in the installation. The foregoing and other features 75 of the invention will be described herein-after more in detail and particularly defined 80 in the appended claims.

The preferred embodiment of the invention is illustrated in the accompanying drawings, in which—

Fig. 1 illustrates the complete apparatus, 85 partly in elevation and partly in section.

Fig. 2 is an enlarged detail view of a portion of one of the similarly inclined sections, illustrating the system of down-pipes for the liquid and the vapor cap arrangement connecting each chamber. 90

Fig. 3 is a view, partly in elevation and partly in section, on line 3—3 of Fig. 2.

Fig. 4 is a view, partly in plan and partly in section, of one of the chambers. 95

Figs. 5 and 6 are views, partly in elevation and partly in section, on lines 5—5 and 6—6 of Fig. 1, and

Fig. 7 is a view in end elevation illustrating the means for connecting the two inclined sections of the still proper. 100

Referring to the drawings in detail, the improved distilling apparatus comprises substantially five sections, to wit: A, B, C, D and E; section A representing the condenser, B the doubler, C and D the distilling columns proper, and E the heater for the alcohol-containing substance to be treated, which section we have termed the beer heater, 105

all of said sections being arranged in succession from the top to the bottom of the apparatus, in the order named.

The condenser A is preferably arranged 5 directly above the doubler B, and as illustrated, said condenser and doubler comprise troughs or housings 1 and 2 having mounted therein a series of tubes 3 and 4 respectively, the said tubes being slightly inclined. The 10 tubes 3 are connected at their ends by header sections 5 and 6, and the tubes 4 of the doubler B are similarly connected by header sections 7 and 8. The header sections 5 and 6 of the condenser A are mounted within the 15 housing 1 on cross-partitions 9 and 10, and the header sections 7 and 8 of the doubler B are similarly positioned by cross-partitions 11 and 12. These series of tubes 3 and 4 of the condenser A and doubler B, respectively, 20 are also supported by intermediate partitions 13 and 14. Upon referring to the drawings it will be noted that the end partitions 9 and 11, supporting the elevated ends of the tubes 3 and 4, are provided with openings 9' and 11' to permit the passage of the cooling fluid admitted within the housings 1 and 2 of the condenser and doubler for the purpose to be hereinafter fully described. 25

In this same connection it will be noted that 30 the partitions 13 allow for the fluid passing over the top thereof and that the partitions 14 are somewhat similarly constructed to the partitions 9 and 11, to permit the cooling fluid to flow beneath said partitions. The cross-partitions 10 and 12, supporting the header sections 6 and 8 of the depressed ends of the tubes 3 and 4, do not extend to the top edge of the troughs or housings 1 and 2, in order 35 to permit the cooling fluid to pass up and over said partitions 10 and 12. With this construction of cross-partitions, it will be noted that as the cooling fluid first enters the condenser A, by the pipe 15, it will be 40 caused to flow under the partition 9, over the partition 13, under the partition 14, and over the lower end partition 10, thereby causing a continuous circulation of the fluid around and through the tubes 3. The fluid will 45 continue to rise in trough 1 until it reaches the level of the pipe 16, whereupon it will pass through pipe 16 into the bottom portion of the trough 2, housing the doubler B, whereupon 50 said fluid will be conducted through said doubler B in a manner similar to its course through the condenser A. The fluid will continue to flow into the trough 2 of the doubler B until it reaches the level of pipe 17 after which said fluid will be conducted 55 over to the waste by pipe 17' or by way of the by-pass 18 through a regulating valve 18' into the upper end of distilling column 19 of section C of the apparatus.

The upper end of the distilling column 19 60 is also in communication with the lower end of the tubes 4 of the doubler B by way of a

series of pipes 20, the upper end of the tubes 4 of said doubler being also in communication, by way of a series of pipes 21, with the upper end of the tubes 3 of the condenser A.

For the sake of convenience and clearness of description, it will be here noted that in starting the apparatus, the cooling fluid in the condenser A, by way of pipe 15, is conducted through the condenser and thence 70 through the doubler in the manner specified, and from there it is conducted into the upper end of the distilling column 19, by the by-pass 18, whence it flows downwardly 75 from chamber to chamber, for the purpose and in the manner to be hereinafter more fully described. After the apparatus has been fully started and is under operation, the valve 18' is shut off, and the cooling 80 fluid is allowed to be discharged through the waste pipe 17', and under these conditions it is only used for cooling the tubes 3 and 4 of the condenser A and doubler B. In starting the apparatus, however, this fluid is allowed to pass down the pipe 18 through the 85 valve 18' into the upper end of the distilling column 19.

The distilling column 19 is preferably inclined and provided with horizontally disposed partitions 22 forming a series of chambers. These chambers are connected by a series of exteriorly arranged pipes 23, the inlet ends 24 of said pipes being slightly elevated above the level of the partitions 22 90 and mounted in cross-bars or blocks 25, which bars or blocks establish the liquid level in each chamber. The lower or outlet ends 26 of the pipe 23 are on the same level with the partitions 22, for the purpose to 95 be hereinafter more fully described, this same arrangement being carried out through the length of the distilling column 19 from chamber to chamber, forming a continuous 100 down-pipe arrangement for the downwardly flowing liquid. These down-pipes 23 are furnished with 4-way fittings 23', which not only provide the proper connections for the entrance and exit sections of the down-pipes 23, but also form a simple and ready means 105 of cleaning these pipes by removing the 110 screw plugs in the fittings 23'.

Disposed below the distilling column 19 of section C is another similarly constructed distilling column 27, comprising section D, 110 said column 27 being connected to column 19 by a series of pipes 27', through which the liquid flows from the column 19 into the column 27, passing through said column in the manner as above described for column 19, and finally reaching the lower end of column 27, where it is discharged by a series of pipes 28 into the heating chamber 29 115 formed by a partition 30 arranged within a housing 31, and comprising the section E, 120 hereinbefore referred to as the beer heater.

To the heating chamber 29, steam is admitted at 32, whereby the downwardly flowing liquid is raised to the sufficient temperature for vaporizing the same. As the liquid continues to fill chamber 29 it will eventually pass out of said chamber through the inverted U-shaped pipe 33, mounted in the partition 30, into the chamber 34 inclosing a series of tubes 35, the ends of said tubes being connected by header sections 36 and 37, said header sections in turn being supported within the chamber 34 by cross-partitions 38 and 39. In addition to the cross-partitions 38 and 39, the intermediate portions of the tubes are supported by cross-partitions 40 and 41. These partitions 38, 39, 40 and 41 are so constructed as to permit the heated liquid coming from the chamber 29 through the pipe 33 to flow over the partition 38, under the partition 41, over the partition 40, under the partition 39, and finally discharge through the pipe 42, as the liquid rises sufficiently within the chamber 34 to the level of the discharge end of the outlet pipe 42. As this liquid flows in and around the tubes 35, during its passage through the chamber 34, said tubes will be heated, so that, as the alcohol-containing substance or liquid enters said tubes, by way of the pipe 43, said alcoholic liquid will be likewise heated. This alcoholic liquid or beer is not admitted to the tubes 35 until hot water or similar fluid begins to flow out of pipe 42, which will indicate that the apparatus is ready and in proper condition to start the distilling operation.

As the beer or alcoholic liquid is heated in the tubes 35, it is caused to rise and flow upwardly through the pipe 44 into the upper end of the distilling column 27 by way of branch pipes 45, and also, if desired, into the lower end of distilling column 19 by branch pipes 46. The correct point of entrance, however, must be decided according to circumstances and experience. From the points of admission, the beer flows downwardly in the manner above described for the water, displaces the water, and is de-alcoholized in its downward passage, and finally leaves the still by the pipe 42. It is to be understood that as the downcoming liquid through the distilling columns 19 and 27 enters the heating chamber 29 by the pipes 28, the same is heated to a boiling temperature, the vapor from which rises through the distilling columns 27 and 19 from chamber to chamber, heating the water in each chamber as it rises. This vapor at first is merely water vapor, but upon the starting of the apparatus and the admission of the beer by way of pipe 44 and branch pipes 45 and 46 to the distilling columns 27 and 19, respectively, the beer will flow downwardly, displacing the water, the distillation thereof will begin, and the vapors eventually rising will be alcoholic vapors.

To permit the rising of the vapors from chamber to chamber, each of the partitions 22 is provided with a series of openings 47, over which is placed a strip or bar 48, preferably of wood and provided with vertically disposed holes or openings 49, registering with and forming a continuation of the holes 47 in each horizontal partition 22. The bar 48 is also provided with transverse, horizontally disposed openings 50, whereby the liquid in each chamber may be permitted to flow each side of said bar 48. Above the bar 48 is placed an inverted trough or cap 51, known as a vapor cap, which vapor cap is slightly spaced from the bar 48, the lower side edges of said vapor cap being preferably serrated and extending below the top edge of the partly inclosed bar 48, in which position said lower edges of the vapor cap will be below the liquid level in said chamber, whereby a liquid seal will be provided, so that the vapors rising from chamber to chamber and passing upwardly through the openings 47 and 49 of the partition and bar, respectively, will be deflected downwardly by the inner vertical sides of the vapor cap 51, and in escaping will be forced to bubble upwardly through the liquid covering the partition 22. The bottom edges of both vertical sides of the vapor cap 51 are notched or serrated, as shown at 52, the purpose and effect of the notching being to divide the flow of vapor into numerous small streams. The alcohol contained in the liquid covering the partitions 22 of the various chambers is of lower boiling point than the temperature of the vapor rising from the heating chamber 29, and the passage of the vapor through the liquid under the vertical sides of the vapor cap 51 causes a portion of the alcohol in the liquid to vaporize, so that the vapor increases and the liquid decreases in alcoholic content. The vapor rises and passes from chamber to chamber in the manner described and by the time it has reached the point of entrance for the beer at the branch pipes 45 and 46, it has been considerably reduced in temperature and considerably enriched in alcoholic vapors. After passing the point of entrance of the beer by way of branch pipes 45 and 46, the vapor rising through the alcohol and the temperature difference between the vapor and the liquid will be slight, so that water vapors will be condensed by the passage of the vapor through the liquid and the alcoholic content of the vapors will be increased by the removal of the water, the alcoholic vapors of low boiling point not being condensed to the same extent as the water vapors. The water resulting from this condensation flows downwardly through pipes 23 and eventually leaves the still through pipe 42. The alcoholic vapors leaving the uppermost chamber of the distilling column 19 pass through

pipes 20 and enter the doubler section B, passing through tubes 4, pipes 21, and into tubes 3 located in the condenser section A. The vapors entering the tubes 4 are still laden with a considerable amount of water vapor, and tubes 4 are therefore kept at a temperature which will condense the most water with the least amount of alcohol. The condensate carrying with it a portion of alcohol, also condensed, flows downwardly through pipes 20, back into the distilling column 19, where the alcohol is re-vaporized and returned to the doubler B, while the water continues downward and eventually leaves the still by pipe 42. The tubes 3 in the condenser A are kept at a temperature which will condense the vapors as completely as possible. The condensate, which is alcohol of more or less high proof, leaves the still by pipe 53 and thence to receiving tanks provided for the purpose. The proof of the alcohol is due to the temperature maintained in tubes 4. If the temperature be low, the result will be a high proof condensate from pipe 53. If the temperature be high, the proof of the condensate will be low. Pipes 20, 27' and 28 are the only elements in the apparatus which are common to the ascending vapor and the descending liquid, as elsewhere the course of the vapor is entirely separate from that of the liquid and the operation of the apparatus is continuous.

As hereinbefore stated, by inclining the main distilling columns 19 and 27, a greater horizontal area of the various chambers is obtained than would be possible with distilling columns of the same cross-section vertically disposed, giving a greater capacity in proportion to its cross-section, which capacity, to a great extent, governs the bubbling area of the vapor caps, all of which advantages will be perfectly obvious to one skilled in the art.

Another great advantage in inclining these main distilling columns is that the upper sides thereof can be very conveniently made removable, either in whole or in part, whereby instant access may be had to the interior of the still without disturbing any other part of the distilling column, if at any time it should become necessary for the purpose of inspection or repairs.

It will also be apparent that the construction and arrangement of the down-pipes 23, with particular reference to the 4-way fittings 23', make it an exceedingly simple and expeditious operation to clean out said pipes, and also the various chambers connected thereby, by removing the desired screw plugs in the couplings or fittings 23', and thereafter properly directing into said down-pipes the cleaning fluid, such as steam or the like, according to whether it is desired to clean the chambers or simply the pipe sections.

It is also contemplated to provide, if necessary, auxiliary down-pipes, as shown at 56 in Fig. 2, which pipes are preferably vertically disposed and arranged on the vertical sides of the inclined distilling columns. The inlet and outlet openings on these vertically disposed auxiliary pipes are arranged in the same manner as the inlet and outlet ends of the down-pipes 23. In both arrangement of pipes, the fluid is admitted to the respective chambers at a point approximately level with the bottom of said chambers, which will prevent the vapor rising from chamber to chamber from passing through said pipe.

What we claim is:

1. In a continuously operating still, a distilling column inclined at an angle between the perpendicular and horizontal and comprising a series of successively communicating chambers for the downward flow of liquid therethrough, each of said chambers having a horizontally disposed floor to provide an extensive bubbling surface, each floor having a capped opening for the upward flow of vapor through the successive chambers, and means for maintaining liquid at a level in each chamber to effect normally a seal for the capped floor-opening.

2. In a continuously operating still, a distilling column inclined at an angle between the perpendicular and horizontal and comprising a series of successively communicating chambers for the downward flow of liquid therethrough, each of said chambers having a horizontally disposed floor to provide an extensive bubbling surface, each floor having a plurality of capped openings for the upward flow of vapor through the successive chambers, and means for maintaining liquid at a level in each chamber to effect normally a seal for the capped floor-openings.

3. In a continuously operating still, a distilling column inclined at an angle between the perpendicular and horizontal and comprising a trunk and a series of spaced partitions extending horizontally across the trunk to form therein successive chambers, each partition forming the floor of an upper chamber and the ceiling of the adjacent lower chamber and each partition having a plurality of capped openings for the upward flow of vapor through the trunk, and means for maintaining liquid in each chamber at a level to effect normally a seal for the capped floor-openings.

4. In a continuously operating still, a distilling column inclined at an angle between the perpendicular and horizontal and comprising a trunk and a series of spaced partitions extending horizontally across the trunk to form therein successive chambers, each partition forming the floor of an upper chamber and the ceiling of the adjacent

- lower chamber and each partition having a plurality of capped openings for the upward flow of vapor through the trunk, means apart from the capped openings for forming communication between successive chambers to permit downward flow of liquid through the trunk, and means for maintaining the liquid in each chamber at a level to effect normally a seal for the capped floor-openings of said chamber. 5. In a continuously operated still, the combination of a heater for the liquid to be treated and a condenser placed above the heater, with a distilling column interposed between and communicating at its respective ends with the heater and the condenser, said column being inclined at an angle between the perpendicular and horizontal and comprising a series of successively communicating chambers for the downward flow of liquid therethrough to the heater, the floors of the successive chambers being horizontally arranged to provide an extensive bubbling surface and each of said floors having a plurality of capped openings for the upward flow of vapor through the successive chambers to the condenser, and means for maintaining the liquid in each chamber at a level to effect normally a seal for the capped floor openings of the chamber. 6. In a continuously operated still, the combination of a heater for the liquid to be treated and a condenser placed above the heater, with a distilling column interposed between and communicating at its respective ends with the heater and the condenser, said column being inclined at an angle between the perpendicular and horizontal and comprising a series of successively communicating chambers for the downward flow of liquid therethrough to the heater, the floors of the successive chambers being horizontally arranged to provide an extensive bubbling surface and each of said floors having a plurality of capped openings for the upward flow of vapor through the successive chambers to the condenser, means for maintaining the liquid in each chamber at a level to effect normally a seal for the capped floor-openings of the chamber, and a separate pipe for conveying heated fluid from the heater into the upper part of the distilling column to flow downwardly through the successive chambers. 7. In a continuously operating still, the combination of a heater for the liquid to be treated and a condenser placed directly above the heater, with upper and lower distilling columns relatively inclined and interposed between the heater and condenser, said columns communicating with each other and respectively with the heater and condenser, and a separate pipe for conveying heated fluid from the heater to either column. 8. In a continuously operating still, the combination of a heater for the liquid to be treated and a condenser placed directly above the heater, with upper and lower distilling columns relatively inclined and interposed between the heater and condenser, 70 said columns communicating with each other and respectively with the heater and condenser, and a separate pipe for conveying heated fluid from the heater to either column. 9. In a continuously operating still, the combination of a heater for the liquid to be treated and a condenser placed directly above the heater, with upper and lower distilling columns relatively inclined and interposed between the heater and condenser, 80 said columns communicating with each other and respectively with the heater and condenser, and a separate pipe for conveying heated fluid from the heater into the upper part of the lower column and the lower part of the upper column. 10. In a continuously operating still, the combination of a heater for the liquid to be treated and a condenser placed directly above the heater, with upper and lower distilling columns relatively inclined and interposed between the heater and condenser, 85 said columns communicating with each other and respectively with the heater and condenser, both of said columns comprising a series of successively communicating chambers for the downward flow of liquid therethrough to the heater, the floors of the successive chambers being horizontally arranged and provided with capped openings for the upward flow of vapor through both columns to the condenser, and means for maintaining the liquid in each chamber of both columns at a level to effect normally a seal for the capped floor-openings of the chamber. 11. In a continuously operating still, the combination of a heater for the liquid to be treated and a condenser placed directly above the heater, with upper and lower distilling columns relatively inclined and interposed between the heater and condenser, 90 said columns communicating with each other and respectively with the heater and condenser, both of said columns comprising a series of successively communicating chambers for the downward flow of liquid therethrough to the heater, the floors of the successive chambers being horizontally arranged and provided with capped openings for the upward flow of vapor through both columns to the condenser, means for maintaining the liquid in each chamber of both columns at a level to effect normally a seal for the capped floor-openings of the chamber, and a separate pipe for conveying heated fluid from the heater to either column. 12. In a continuously operating still, the 105 110 115 120 125 130

combination of a heater for the liquid to be treated and a condenser placed directly above the heater, with upper and lower distilling columns relatively inclined and interposed between the heater and condenser, said columns communicating with each other and respectively with the heater and condenser, both of said columns comprising a series of successively communicating chambers for the downward flow of liquid therethrough to the heater, the floors of the successive chambers being horizontally arranged and provided with capped openings for the upward flow of vapor through both columns to the condenser, means for maintaining the liquid in each chamber of both columns at a level to effect normally a seal for the capped floor-openings of the chamber, and a separate pipe for conveying heated fluid from the heater to either column.

16. In a continuously operated still, the combination of a heater for the liquid to be treated and a condenser placed above the heater, with upper and lower distilling columns relatively inclined and interposed between the heater and the condenser, said columns communicating with each other and respectively communicating with the heater and condenser, both columns comprising a series of successively communicating chambers for the downward flow of liquid to the heater, each of said chambers having a horizontally disposed floor provided with a plurality of capped openings for the upward flow of vapor through the successive columns to the condenser, means for maintaining liquid at a level in each chamber to effect normally a seal for the capped floor-openings, and a separate pipe for conveying heated fluid from the heater to either column.

13. In a continuously operated still, the combination of a heater for the liquid to be treated and a condenser placed above the heater, with a distilling column interposed between and communicating at its respective ends with the heater and condenser, said column comprising a series of successively communicating chambers for the downward flow of liquid therethrough to the heater, each of said chambers having a horizontally disposed floor to provide an extensive bubbling surface and each floor having a plurality of capped openings for the upward flow of vapor through the successive chambers to the condenser, and means for maintaining liquid at a level in each chamber to effect normally a seal for the capped floor-openings.

14. In a continuously operated still, the combination of a heater for the liquid to be treated and a condenser placed above the heater, with upper and lower distilling columns relatively inclined and interposed between the heater and the condenser, said columns communicating with each other and respectively communicating with the heater and condenser, both columns comprising a series of successively communicating chambers for the downward flow of liquid to the heater, each of said chambers having a horizontally disposed floor provided with a plurality of capped openings for the upward flow of vapor through the successive columns to the condenser, and means for maintaining liquid at a level in each chamber to effect normally a seal for the capped floor-openings.

15. In a continuously operated still, the combination of a heater for the liquid to be treated and a condenser placed above the heater, with upper and lower distilling columns relatively inclined and interposed between the heater and the condenser, said col-

umns communicating with each other and respectively communicating with the heater and condenser, both columns comprising a series of successively communicating chambers for the downward flow of liquid to the heater, each of said chambers having a horizontally disposed floor provided with a plurality of capped openings for the upward flow of vapor through the successive columns to the condenser, means for maintaining liquid at a level in each chamber to effect normally a seal for the capped floor-openings, and a separate pipe for conveying heated fluid from the heater to either column.

16. In a continuously operated still, the combination of a heater for the liquid to be treated and a condenser placed above the heater, with upper and lower distilling columns relatively inclined and interposed between the heater and the condenser, said columns communicating with each other and respectively communicating with the heater and condenser, both columns comprising a series of successively communicating chambers for the downward flow of liquid to the heater, each of said chambers having a horizontally disposed floor provided with a plurality of capped openings for the upward flow of vapor through the successive columns to the condenser, means for maintaining liquid at a level in each chamber to effect normally a seal for the capped floor-openings, and a separate pipe for conveying heated fluid from the heater to the upper part of the lower column and to the lower part of the upper column.

17. In a continuously operating still, a distilling column inclined at an angle between the perpendicular and horizontal and comprising a series of chambers with each having a horizontal floor and with each chamber having a liquid inlet and a liquid outlet at a higher level than the inlet to maintain at a predetermined level the liquid flowing through the chamber, an exterior pipe forming a communication between the outlet of each chamber with the adjacent lower chamber, and the horizontal floor of each chamber having a plurality of capped openings for the flow of vapor therethrough from the adjacent lower chamber, said openings being normally sealed by the liquid-level maintained in the chamber to effect a bubbling action as the vapor passes through said openings.

18. In a continuously operating still, a distilling column inclined at an angle between the perpendicular and horizontal and comprising a series of successively communicating chambers for the downward flow of liquid therethrough, means for maintaining the liquid at a predetermined level in each chamber, each of said chambers having a horizontal floor provided with a series

of openings for the upward flow of vapor into the chamber from the adjacent chamber below, a bar fixed on the floor with upwardly extending openings registering with the series of floor-openings and said bar having transverse passages adjacent the floor for the flow of liquid from one side of the bar to the other, and a longitudinal cap extending over the bar to deflect the vapor below the liquid-level maintained in the chamber. In testimony whereof we affix our signatures.

JOHN PRESTON FOSTER.
ALBERT F. MISNER.
